M. C. COPIES

ENGINE CONTROL DEVICE

Filed Jan. 30, 1922

Inventor
Mason C. Copes

By Lyman & Lyman attys.

UNITED STATES PATENT OFFICE.

MASON C. COPIES, OF LOS ANGELES, CALIFORNIA.

ENGINE-CONTROL DEVICE.

Application filed January 30, 1922. Serial No. 532,750.

To all whom it may concern:

Be it known that I, MASON C. COPIES, a citizen of the United States, residing at Los Angeles, in the county of Los Angeles and 5 State of California, have invented a new and useful Engine-Control Device, of which the following is a specification.

This invention relates to an engine control device and is particularly directed to 10 a device having a cooperative function with a forced feed lubricating system.

An object of the invention is to provide a device by which the supply of motive fluid or mixture to the engine is regulated according to the pressure in the lubricating 15 system.

Another object is to provide a device for controlling the supply of mixture from the carburetor to the intake manifold of an internal combustion engine having a forced 20 feed lubricating system, whereby said supply is automatically cut off when the pressure in the lubricating system falls below a point of safety.

25 A further object is to provide a manually operative means for operating the device independently of the pressure conditions in the lubricating system so as to permit a starting of the engine.

30 Various other objects and advantages will be more fully apparent from the following description of the accompanying drawings, which form a part of this disclosure, and which illustrate a preferred embodiment of 35 the invention.

Of the drawings:

Fig. 1 is an elevation of a conventional type of internal combustion engine with my improved control device applied thereto.

40 Fig. 2 is an enlarged elevation, partly in section, of the control device, and

Fig. 3 is a section on line 3—3, of Fig. 2.

In the embodiment of the invention illustrated in the drawings, there is provided 45 a conduit 1 interposed between the carburetor 2 and the intake manifold 3 and provided with flanges 4 for attachment to the flanges of said carburetor and manifold.

50 A horizontal shaft 5 journaled in the walls of said conduit carries a valve disc 6 which controls the passage of mixture from the carburetor to the intake manifold. The shaft 5 extends through the wall of the 55 conduit 1 and has secured thereto an operating lever 7 having a pin and slot con-

nexion with a piston rod 8 so that as said rod is moved down or up the valve 6 will be closed or opened as the case may be.

The piston rod 8 extends through a bushing 9 and connects with a piston 10 having a sliding fit in a cylinder 11. The lower portion of the cylinder communicates by a pipe 12 with the forced feed lubricating system which includes a suitable oil pump 60 13 supplying lubricant under pressure to the various bearings of the engine in the usual well known manner.

The lower portion of the cylinder 11 is 65 enlarged and has an inclined wall portion 14 providing an annular seat and the lower portion of the piston 10 is similarly enlarged and provided with an inclined or conical portion 15 constituting a valve for cooperation with the seat 14 when the piston is in elevated position so as to form a positive seal preventing the oil from escaping upwardly past the piston. A spring 16 interposed between the piston and the bushing 9 functions to return the piston to 70 its depressed position when the pressure in the lubricating system falls below a point of safety, the tension of the spring being regulated by screwing the bushing upwardly or downwardly in the cylinder.

75 The cylinder is supported by a bracket 17 extending from the conduit 1 and is retained clamped upon said bracket by a strap member 18, the strap member also clamping the end of a tube 19 leading to the dash 80 board 20. A flexible wire 21 extends through said tube and upwardly through a slot 22 in the end of the lever 7 and has secured to its free end an abutment stop 23, the dash board end of the wire being provided with a handle or button 24 by which the wire may be pulled.

85 With the engine running and the forced feed lubricating system in operation, the device will be maintained in the condition 100 illustrated, the pressure maintained in the lubricating system being exerted upon the lower end of the piston 10, maintaining it in elevated position and the valve 6 in open position permitting a full supply of mixture 105 to flow from the carburetor into the intake manifold.

If by a clogging of the lubricating system or if for any other reason, the pressure 110 therein is not maintained, the spring 16 will cause a lowering of the piston and a closing of the valve 6 to prevent a continued oper-

ation of the engine such as would cause a burning out of the bearings.

Thus I have provided a control device by which the supply of mixture to the engine is regulated with respect to the pressure maintained in the lubricating system.

As it is evident that with the engine at rest, there will be no pressure in the lubricating system until the engine is first started, means must be provided for independently opening the valve 6 so as to permit an initial starting of the engine. Such means includes the flexible wire 21 which is manually pulled outwardly at the dash board when desired to start the engine. By so pulling upon the wire 21, the abutment stop 23 engages the top surface of the lever 7 and moves the parts to the position shown in Fig. 2 causing an opening of the valve 6 regardless of the pressure conditions in the lubricating system. As soon as the engine is running properly the wire 21 is released and the device then assumes its automatic control under the influence of the pressure within the lubricating system.

Having described my invention I claim:

1. In combination with an engine having an inlet conduit for the explosive mixture and a forced feed lubricating system, a valve controlling the flow of explosive mixture through the inlet conduit, a valve actuator movable with the valve in response to variations in the pressure in the lubricating system, and independent means having an operating handle at the dash for opening the valve regardless of pressure conditions in the lubricating system.

2. In combination with an engine having an inlet conduit for explosive mixture and a forced feed lubricating system, a valve controlling the flow of explosive mixture through the inlet conduit, a valve actuator having a direct connection with said valve and movable in one direction in response to pressure in the lubricating system to open the valve, means for moving the actuator and valve in a reverse direction and functioning with a decrease in said pressure to close the valve, and independent means having an operating handle at the dash for moving the valve to open position regardless of pressure conditions in the lubricating system.

3. In combination with an internal combustion engine having an intake manifold and a carbureter, a forced feed lubricating system, a valve controlling the flow of explosive mixture from the carbureter to the manifold, a cylinder communicating with the lubricating system, a piston within the cylinder connected to operate the valve and maintained in position to hold the valve open by pressure within the lubricating system, means for moving the piston into a position to close the valve upon a decrease

in said pressure, and means having an operating handle at the dash for moving the valve to open position regardless of pressure conditions in the lubricating system.

4. In combination with an internal combustion engine having an intake manifold and a carbureter, a forced feed lubricating system, a throttle valve having a valve disc rotatably mounted therein for controlling the flow of the explosive mixture from the carbureter to the manifold, a lever rigidly connected with the valve disc for rotating the same, a cylinder communicating with the lubricating system, a piston within the cylinder connected with the said lever and operating to actuate the lever and close the throttle valve when the pressure in the lubricating system falls, and means operable from the driver's position for operating the said lever at will to open the throttle valve independently of the pressure in the lubricating system and constructed to permit free movement of the lever by the piston.

5. In combination with an internal combustion engine having an intake manifold and a carbureter, a forced feed lubricating system, a throttle valve having a rotatably mounted valve disc for controlling the flow of the explosive mixture from the carbureter to the manifold, a lever rigidly connected with the valve disc for operating the same, a cylinder communicating with the lubricating system, a piston mounted within the cylinder, said piston having a substantially conical portion, and said cylinder having a seat for the conical portion of the piston whereby the piston operates as a valve to prevent the oil under pressure from passing the valve, means connecting the piston with said lever to enable the pressure in the lubricating system to control the valve, a spring within the cylinder for closing the throttle valve when the pressure in the lubricating system falls, and a flexible pull-wire operable from the driver's position and having means for engaging the lever to open the throttle valve at will independently of the pressure in the lubricating system and permitting the free movement of said lever by the said piston.

6. In combination with an internal combustion engine having an intake manifold and a carbureter, a forced feed lubricating system, a throttle valve having a rotatable valve disc mounted therein for controlling the flow of the explosive mixture from the carbureter to the manifold, a cylinder communicating with the lubricating system having a portion of reduced diameter and a portion of enlarged diameter, with a conical seat connecting the same, a piston mounted to slide within the cylinder, having a conical face to come upon the seat and prevent flow of the oil past the piston when on its seat, a piston rod extending from the

5 piston and connected with the said lever whereby the pressure of the oil in the lubricating system normally holds the valve disc so that the throttle valve is wide open, a
5 spring exerting its force in a direction to close the throttle valve when the pressure in the lubricating system falls, and means operable from the driver's position for engaging the lever to open the valve at will inde-
10 pendently of the pressure existing in the lubricating system, and constructed to permit free movement of the said lever by the piston.

7. In combination with an internal com-
15 bustion engine having an intake manifold and a carburetor, a forced feed lubricating system, a throttle valve controlling the flow of the explosive mixture and having a valve disc rotatably mounted therein, a cylinder
20 having a portion of reduced diameter and a portion of enlarged diameter, with a seat portion connecting the same, the enlarged portion of said cylinder being in communication with the lubricating system, a piston
25 movable in the cylinder and having an en-

larged portion to cooperate with the seat portion to prevent escape of oil past the piston when on its seat, a bushing at the end of the reduced portion of the cylinder, a piston-rod connected with the piston and mounted to slide through the bushing, a lever rigid with the valve disc and connected with the piston-rod, whereby the pressure in the lubricating system normally holds the throttle-valve wide open, a spring within the reduced portion of the cylinder between the piston and the said bushing, exerting its force in a direction to close the throttle valve, and a pull-wire operable from the driver's position and having a connection to the said lever, enabling the same to operate the throttle valve independently of the pressure in the lubricating system, and permitting free movement of the lever by the piston.

Signed at Los Angeles, California, this 45
23d day of January, 1922.

MASON C. COPES.
